HOT WATER HEATER

Gordon Hatch, Milwaukee, Wis., assignor to Hatco Corporation, Milwaukee, Wis., a corporation of Wisconsin

Filed Oct. 23, 1959, Ser. No. 58,043

Term of patent 14 years

(Cl. D81—2)

Fig. 1 is a front perspective view of a water heater embodying the design.

Fig. 2 is a plan view thereof.

Fig. 3 is a fragmentary view in side elevation of the top right hand portion of the water heater as shown in Fig. 1.

The rear of the heater is substantially plain and the side not shown is allochirally identical with the side shown.

I claim:

The ornamental design for a hot water heater, as shown and described.
